D. MARTIN

FURNACE

Filed Nov. 27, 1926

BY

INVENTOR
David Martin
ATTORNEY

UNITED STATES PATENT OFFICE.

DAVID MARTIN, OF MILWAUKEE, WISCONSIN.

FURNACE.

Application filed November 27, 1926. Serial No. 151,059.

This invention relates to a new and useful device in the nature of a grate shaking device for furnaces.

The object of the invention is to provide 5 a grate shaking device of novel construction and arrangement of parts, hereinafter more fully described, claimed and illustrated in the accompanying drawings in which:

Fig. 1 shows a front elevational view of 10 a furnace embodying my improved device, partly fragmentary so as to expose certain interior parts.

Figs. 2 is a longitudinal partly sectional view taken on the line 2—2 of Fig. 1.

15 Fig. 3 is a transverse sectional plan view taken on the line 3—3 of Fig. 1.

Fig. 4 is an enlarged fragmentary detail view thereof.

The outer casing 10, the inner casing 11, 20 the top member 12, the stack 13, the flue tubes 14, the fire door 15 hinged to the outer casing 10, the ash door 16 similarly attached to the outer casing 10, at or near the lower end thereof, are the conventional elements 25 of a furnace such as is generally employed for heating purposes. It being understood that I do not necessarily limit the use of my invention to furnaces of the type above described and set forth, but to all classes 30 of furnaces such as ordinarily used for all purposes.

As here embodied my improved device comprises a lever 20, pivotally attached at one extremity, as at 21, to the sector member 35 22. The lever 20 is provided with a handle 23 and has adjacently pivoted thereto, a lever 24, to which is pivotally attached a rod 25, extended lengthwise of the first mentioned lever 20. The lower extremity of the 40 rod 25 is normally held in engagement with any desired one of the notches 26 formed in the sector member 22 by means of the expansion spring 27, positioned or wound on the rod 25 and superimposed between the 45 lugs 18 and 29 of the lever 20, in which the rod 25 is slidably mounted. The above described construction being such as will permit the lever 20 to be pivoted when the lever 24 is pressed or forced inwardly against the 50 handle 23, which will disengage the rod 25, which normally holds the lever 20 in any desired fixed position.

The arm 30 is pivotally attached at its extremities intermediate the extremities of the 55 lever 20 and to one extremity of the lever

31. The lever 31 is pivotally attached, as at 32, to the extended element 33 of the sector member 22. The elongated aperture 33 is formed intermediate the extremities of the lever 31.

The pin 34 is slidably engaged in the elongated aperture 33 and is provided with an enlarged head 35' and has threadedly attached thereto a threaded member 39', a nut or the like, as a means of holding the pin 34 in any desired position in the said elongated slot. The rod 35 is pivotally attached at its extremity, to the extended element 37' of the pin 34, which is provided with a threaded axial aperture to receive the threaded member 38, a machine screw or the like, as a means of holding the rod 35 in place. The above described construction being such as will permit the movement of the rod 35 to be varied or changed as 75 may be desired, by sliding the pin 34 in the elongated aperture 33. The rod 35 is pivotally attached at one extremity to the lever 36, which is attached to the shaft 37, rotatively mounted in a support 37^a attached to the lining 38' or bed of the ash pit. It being understood that the sector member 22 is mounted on the floor surface, adjacent to the furnace, and that the rod 35 is extended 80 inside the furnace, in the ash pit, preferably 85 in proximity to the rear portion of the inner casing 11. The gear 38^a is attached to the shaft 37 and meshes with teeth formed or cut in the rack bar 39, slidably mounted in the supports 40 and 41 attached to the outer 90 casing 11. The rack bar 39 is provided with second teeth 42 and mesh with the segment gears 43 attached to the grate bars 44, rotatively mounted in the furnace, as is customary practice. The grate bars 44 are positioned in alignment with and between the horizontal portions 45 of the fire box heating flues 14, such as generally used in furnaces.

The above described construction being 100 such as will permit the lever 20 when pivoted, to rock the grate bars 44, as may be required to shake the said grate bars.

It is obvious that I have provided a means of uniformly and evenly shaking a plurality 105 of grate bars, so as to maintain an even and uniform fire bed, as is highly desirable and in accord with greater efficiency.

It is further obvious that I have provided 110 a means of varying or changing the amount

of the said uniform movement, as is desirable to prevent the dumping of the fire when fine grades of coal are used.

Having thus described my invention, what I claim as new and desire to protect by Letters Patent of the United States is as follows:

- 5 1. In a furnace of the class described, spaced apart rotatively mounted grate sections having gear segments attached thereto, a rod disposed within said furnace and slidably mounted at its extremities in the walls thereof, teeth on the upper edge of said rod engaged with the teeth of said gear segments, a standard mounted in the floor of said furnace having an aperture therein, a shaft journaled in said aperture, a gear attached to said shaft, teeth on the lower edge of said slidably mounted rod meshed with 10 the teeth of said gear and actuating mechanism operatively connected with said gear and mounted externally of said furnace for oscillating the same to reciprocate said rod for rotating said grate section.
- 15 2. In a furnace of the class described,

spaced apart grate sections disposed across the interior thereof and rotatively mounted thereon, gear segments mounted on the rear ends of said grate sections, a standard mounted on the floor of said furnace adjacent the rear wall thereof, a shaft rotatively mounted on said standard, a gear rigidly mounted on said shaft, a rod slidably mounted at its extremities in apertures in the sides of said furnace and disposed across the rear thereof comprising upper rack teeth meshed with the teeth of the gear segments of said grate sections and lower rack teeth meshed with the teeth of said gear, a crank attached to said shaft for rotating the same, a link attached to said crank and extending forwardly through the front wall of said furnace and actuating mechanism operatively connected with said link and disposed externally of said furnace for reciprocating 40 said rod to rotate said grate sections.

In testimony whereof I have affixed my signature.

DAVID MARTIN.
